Patented Nov. 28, 1922.

UNITED STATES PATENT OFFICE.

LEE B. CARPENTER, OF ROCHESTER, NEW YORK, ASSIGNOR TO THE CARPENTER SHOE COMPANY, INC., OF ROCHESTER, NEW YORK, A CORPORATION OF NEW YORK.

SHOE.

Application filed October 17, 1921. Serial No. 508,159.

To all whom it may concern:

Be it known that I, LEE B. CARPENTER, a citizen of the United States of America, residing at Rochester, in the county of Monroe and State of New York, have invented 5 certain new and useful Improvements in Shoes, of which the following is a specification.

My invention relates to a shoe and method 10 of making the same, and has for its chief purpose to afford a structure particularly applicable to the soft sole type of shoe, such as used for infants, and which can be manufactured economically, and possesses lasting 15 wearing qualities.

More particularly, the invention has for its purpose to afford a shoe with an integral or one-piece ground engaging sole, which is attached to the upper in such a 20 manner as to permit of maximum wear on the sole, while protecting the upper and also giving the appearance of a double soled shoe.

An additional object of the improvement 25 is to enable using a comparatively thick integral sole, thus obtaining the durability and wear of a double sole, while eliminating the additional expense of a double sole and the stiffness which characterizes the 30 latter, owing to the cementing together of inner and outer soles.

The invention also includes certain other improved details, all of which will appear clearly from the following description when 35 read in conjunction with the accompanying drawing, the novel features being pointed out in the claim following the description.

In the drawing:

Figure 1 is a side elevation of an infant's 40 shoe constructed in accordance with a preferred embodiment of the invention;

Figure 2 is a perspective view of my improved form of sole;

Figure 3 is a sectional view of the sole;

Figure 4 is a sectional view of the upper 45 and sole stitched together and before being turned, and

Figure 5 is a similar sectional view of the upper and sole in their final relationship after they are turned.

The invention may be carried out in a 50 number of ways and is applicable to various types and styles of shoes or other foot-wear, and for purpose of illustration, I have 55 selected an infant's shoe as an example be-

cause the invention has special application to this particular field, owing to the very substantial saving that can be effected while at the same time improving the shoe in its wearing and flexible qualities. 60

In the structure shown, and according to the preferred method, I proceed by taking a comparatively thick, integral or one-piece sole 1 of the desired contour and cutting away or channelling the lower part thereof 65 at its outer edge, as designated at 2. While the channel 2 appears at the upper part of the sole, with reference to Figures 2, 3 and 4, it is at the lower part of the sole with reference to Figure 5, which represents its 70 final relationship to the upper, and I, therefore, refer throughout the specification and claim to the channel or cut away portion 2 as located at the lower part of the sole. In cutting away the sole at 2, I also preferably 75 undercut the upper part of the sole as at 3, thus permitting the reduced or comparatively thin attaching portion 4, which is formed by the channel 2, to bend upwardly 80 more readily from the lower ground engaging part of the sole, as shown in Figure 5, and also permitting said lower part of the sole to extend outwardly slightly beyond the attaching portion 4. This arrangement affords an efficient and durable tread, and 85 also gives the desired effect, in appearance, of a double soled shoe.

In constructing a shoe according to my invention, the upper is first laid upon the sole in the manner shown in Figure 2, and 90 stitched to the attaching portion 2. Thereafter, the upper and sole are turned or reversed so that they assume the general relation illustrated in Figure 5 with the attaching portion located in a vertical plane, 95 or at a right angle to the body of the sole, the upper being bent upon itself at its lower edge where it is attached to the sole. By this arrangement of the sole attaching portion in a vertical position, a pocket or channel is afforded between the opposite walls of the sole attaching portion, over the body of the sole, to receive a thick insole, and the upper is maintained sufficiently high 100 above the sole to prevent its contact with the ground and consequent wearing. It will be seen from Figure 5 that the upper is secured to the attaching portion of the sole at a point substantially above the upper part of the sole, so that the sole can be entirely worn 110

- through before the upper starts to wear by contact with the ground. Thus maximum durability and wear is attained, while still securing the characteristics of a soft soled shoe. The sole is preferably made from a chrome split or other suitable soft leather, and being in one piece, has greater flexibility than a sole made of two or more thicknesses cemented together, and my improvement is, 5 in consequence, especially adapted to infants' and similar shoes where it is important to secure adequate wearing qualities combined with the necessary yieldability of the sole to the foot.
- 10 The construction disclosed may be modified without departing from the fundamental novel features of the invention, and this application is intended to cover any 15 footwear construction embodying an integral or one-piece ground engaging sole having a reduced integral attaching portion pro-

jecting upwardly therefrom and an upper secured to the attaching portion, which is preferably formed by channelling or cutting away the lower part of the sole at its 25 edge.

I claim:

20 A soft sole shoe for infants, comprising a one-piece ground engaging sole having an integral attaching portion extending upwardly and located in a vertical plane, affording a pocket on the upper surface of the sole for receiving an insole, and an upper having its edge bent upon itself and secured to said vertical attaching portion of the sole, 35 said vertical attaching portion being of sufficient width so that the lowest portion of the upper is located above the upper surface of the body portion of the sole.

In witness whereof, I have hereunto 40 signed my name.

LEE B. CARPENTER.
